UNITED STATES PATENT OFFICE.

JOHANNES ROBERT CARL AUGUST, OF HALIFAX, ENGLAND.

RIVET OR THE LIKE HEATING FURNACE.

Application filed June 2, 1920. Serial No. 386,089.

(GRANTED UNDER THE PROVISIONS OF THE ACT OF MARCH 3, 1921, 41 STAT. L., 1313.)

To all whom it may concern:

Be it known that I, JOHANNES ROBERT CARL AUGUST, subject of the King of Great Britain, residing at Halifax, in the county 5 of York and Kingdom of England, have invented certain new and useful Improvements in and Relating to Rivet or the like Heating Furnaces (for which I have filed application in England Nov. 22, 1916, Patent 10 No. 107,158), of which the following is a specification.

The present invention relates to improvements in rivet or the like heating furnaces, such for instance as furnaces for the annealing of ball races, or again for the heating of billets or rivets, or for other like purposes of the type in which the articles pass automatically or are pushed along an inclined chute from the inlet to the outlet end of the 20 furnace, which chute also usually serves as a flue for the heating gases.

According to the present invention the chute and floor along which the articles pass are covered by a bridge forming the floor 25 of a flue along which the heating gases finally pass.

The present invention is more particularly described with reference to the accompanying drawings, in which:—

30 Figure 1 is a front cross sectional elevation of a furnace according to the present invention,

Figure 2 is a corresponding side cross sectional elevation.

35 In the back wall of the furnace an opening 1 is provided for the insertion of the rivets or the like articles which pass down a chute 2 extending into a heating floor 3 and thence to an outlet 4 diametrically opposite to the opening 1. It will consequently be seen that if the furnace is full of articles, if one is pushed in through the opening 1 a corresponding article would be pushed on to or out of the opening 4. Above the chute 45 and floor 2, 3, is arranged a bridge 5, 6, preferably having a deflecting partition 7, which, being covered by the furnace gases on its top surface in their exit passage through flue 8, will form a heat radiating surface for 50 the articles to be heated and will consequently increase the efficiency of the furnace. There are passages 10 arranged on

either side of the floor 3 which connect the combustion space above the grate 9 with the chamber directly above said floor. The floor 55 is solid throughout, and these passages are formed by cutting away a portion of the floor and forming flues for said cut away portion. The furnace gases pass from the combustion space above the grate 9 through 60 these passages 10 and thence over the articles on the floor 3. The furnace gases on the way to the chimney 11 pass rearwardly through the flue 8 and thus the bridge 5 becomes heated, and this in turn forms thereof 65 a radiating surface which aids in heating the articles and consequently increases the efficiency of the furnace.

The furnace is provided on the side having an inlet opening 1 with an opening such 70 as 12 for the insertion of fresh fuel for the furnace and on the opposite side, that is to say the same side as has the opening 4, with an opening 13 for the removal of ash or refuse.

75 The openings 1, 4, 12, 13 may be normally closed by suitable doors as desired.

I declare that what I claim is:—

1. A rivet or the like heating furnace having an inlet opening on one side for the articles to be heated leading by means of a chute and a heating floor to an outlet opening diametrically opposite thereto at a lower level, in which the chute and floor are covered by a bridge forming the under surface 80 of a flue along which the heating gases pass in the same direction as the articles passing through the furnace, after these gases have passed directly over the articles in the reverse direction.

90 2. A rivet heating or like furnace, comprising in combination an inlet opening at one side for the articles to be heated, an outlet opening diametrically opposite thereto at a lower level, a chute and heating floor 95 leading from the inlet to the outlet opening, a fuel inlet arranged at the same side of the furnace as the inlet for the articles to be heated, and an ash or refuse outlet on the same side of the furnace as the outlet for 100 the articles to be heated.

3. A rivet heating or like furnace, comprising in combination an inlet opening at one side for the articles to be heated, an out-

let opening diametrically opposite thereto at a lower level, a chute and heating floor leading from the inlet to the outlet opening, a fire grate arranged beneath the floor and a chute, and flues passing on either side of the said floor.

In witness whereof, I have hereunto

signed my name this 29th day of May 1920, in the presence of two subscribing witnesses.

JOHANNES ROBERT CARL AUGUST.
